UNITED STATES PATENT OFFICE.

CORNELIS ZULVER, OF LONDON, AND LAUNCELOT EUSTACE SMITH, OF SOUTH SHIELDS, ENGLAND.

FURNACE.

1,402,703.

Specification of Letters Patent. Patented Jan. 3, 1922.

Application filed August 11, 1919. Serial No. 316,732.

To all whom it may concern:

Be it known that we, CORNELIS ZULVER, a subject of the Queen of the Netherlands, engineer, of St. Helens Court, Great St. 5 Helens, in the city of London, England, and LAUNCELOT EUSTACE SMITH, a subject of the KING of Great Britain, managing director Smiths Dock Company Limited, High Docks, South Shields, in the county of Durham, England, have invented a new and useful Improvement in and Relating to Furnaces, of which the following is a specification.

This invention relates to furnace fronts capable of use when burning either liquid or solid fuel.

According to our present invention, instead of mounting the liquid fuel burner or burners on the fire door, the said burner or burners is or are kept clear of such door or of the fire-opening, for which purpose each burner is arranged in an air-control tube extending through holes of corresponding shape in the front and back plates of the forced draught fronts. These tubes open at their inner ends into the furnace at positions exterior to the fire-opening and are provided at the parts between the said front and back plates with air inlets controlled by suitable dampers or valves. This enables coal and oil to be burnt in conjunction if desired and also reduces the time required for converting from coal to oil working or vice versa, as no pipes or connections have 35 to be disconnected.

In the accompanying drawing—

Fig. 1 is a front elevation of a furnace front constructed according to our invention.

Fig. 2 is a section on the line X, X, Fig. 40 1, and

Fig. 3 a vertical central section of the boiler front with parts broken away and parts omitted.

A, B are the front and back plates of the 45 forced draught front. C is the fire door and D a tubular fire casing having an opening closed by the door C and extending through

the plates A, B. E is a valve actuated by a handle E' and controlling apertures F, which are formed in the upper peripheral 50 wall G of the forced draught front.

H, is one of the tubes in which the burners J are mounted and which extends through circular holes in the plates A, B, its inner end opening into the furnace in a position 55 exterior to the fire-opening D. The tube is here shown as secured in position on the inner side by a loose collar K and set screw L, and on the outer side by a flange M. The tubes H, H are each provided with an annular series of air inlets N, N arranged to open into the space between the plates A, B and controlled by a tubular sliding damper O, which may be operated by means of a suitable handle or handles passing through 60 holes in the burner holder.

What we claim as our invention and desire to secure by Letters Patent is:—

1. A furnace front comprising a front plate and a rear plate spaced therefrom, a casing connecting said front and back plates and forming the walls of an opening for solid fuel, a tube extending through said front and back plates exterior to and on each side of said casing, a liquid fuel burner 70 mounted in each of said tubes, a flange closing the outer ends of said tubes, and means for controlling the admission of air through apertures formed in said tubes between said front and rear plates. 80

2. A furnace front comprising front and rear plates spaced apart, a casing forming a passage between said front and rear plates for the supply of solid fuel to the furnace, air admission apertures formed in the top of 85 said casing, a valve controlling the admission of air through said apertures, a tube on each side of said casing extending through the front and rear plates, air inlet openings formed in said tube, a slide for controlling 90 the admission of air into said tube, and a liquid fuel burner housed in said tube.

CORNELIS ZULVER.

LAUNCELOT EUSTACE SMITH.
